SECURED MATCH VAULT

Tom J. Kuluris, Cleveland, Ohio

Application March 9, 1934, Serial No. 714,801

11 Claims. (Cl. 206—1.5)

My invention relates to improvements in match vaults.

Children like to play with matches, and frequently accidents occur, as a result of the inexperience of children in handling matches; therefore, the desirability of keeping matches in the home in a container inaccessible to children is well recognized.

An object of my invention is therefore to provide a secured match vault, for safety storing matches, in a container, which is inaccessible to children and yet is readily accessible to adults understanding the locking mechanism of the vault.

Another object is to provide a secured match vault, to which quick and ready access may be obtained, for placing a box of matches therein, and removing the individual matches therefrom.

Another object is to provide a locking means, which is operated in a manner not obvious to the ordinary observer, so that special knowledge of the locking means must be acquired before it can be operated.

Still another object is to provide a positive alarm means, which is operated whenever access is obtained to the matches contained in the vault.

While, still another object is, to provide a neat and attractive match vault, which can be produced with a minimum number of parts and at a relatively low cost.

Other objects and advantages of the invention will be apparent during the course of the following description.

In the accompanying drawings, forming a part of this specification, and in which like numerals are employed to designate like parts throughout the same,

Fig. 1 is a perspective view of my new and improved match vault;

Fig. 2 is a central vertical section taken on the line 2—2 of Fig. 1, with the door closed;

Fig. 3 is a view similar to Fig. 2 with the door open;

Fig. 4 is a horizontal section taken on the line 4—4 of Fig. 2;

Fig. 5 is a fragmentary perspective view of the front of the vault illustrating the manner of opening it;

Fig. 6 is a view of the locking mechanism taken on the line 6—6 of Fig. 2; and

Fig. 7 is a sectional view taken on the line 7—7 of Fig. 6.

In the drawings 10 represents a cabinet, preferably made of metal, having a hollow base 11,

and provided on one side with a drawer 12 into which burnt matches may be conveniently dropped through a slot 13. A piece of abrasive material, such as emery paper or sandpaper 14, on which matches may be struck, is mounted in a pocket 15 suitably secured to one side of the cabinet 10, while ornamental flutings 16 are provided on the sides near the front thereof. A conventional thermometer 17, having an indicator needle 18 responsive to temperature changes, is suitably mounted near the top of the front of the cabinet 10.

Access to the interior of the cabinet 10 for placing a box of matches therein, is obtained through a sliding back 19, which is shown removed from the cabinet 10, in Fig. 3, and secured thereto in Fig. 2. For securing the back 19 to the cabinet 10, a lip 20 across the top, and a lip 21 across the bottom of the back 19 are provided, while a ring 22, secured to the outside of the back 19, provides a convenient holding means for manipulating it. A spring-pressed bar 23, is urged upwardly by a spring 24, and a guide plate 25 guides the bar 23 in its up and down movement. The spring-pressed bar 23 permits the back 19 to be inserted at the back of the cabinet 10, and securely locks it thereto.

The means for supporting a box of matches comprise, a match box holder 26 to which is secured a pin 27, one end of which is fitted into a U-shaped slot in a bracket 28, secured to the inside of the cabinet 10, the other end of the pin 27 being fitted in similar slot in a bracket 29, secured to the bottom of the container 10. This construction permits the match box holder 26 to be removably seated in the brackets 28 and 29. A conventional match box is indicated at 30, and is mounted on the holder 26 in a vertical position, as shown in Figs. 2 and 3, a portion of the side of the match box 30 being cut away at 31, to permit matches 32 to roll out onto the holder 26, where they are readily accessible to the user.

Access to the match box 30, supported on the holder 26, is afforded by means of a rotating door 33, operating in a cut away portion 34 near the bottom of the front of the cabinet 10, and rolling on pinions 33a, journaled in inside of the cabinet 10 at the sides of the cut away portion 34. The door 33 is provided centrally with a hollow flange 35 permitting it to be readily grasped in the manner shown in Fig. 5, and is shown in its closed, or locked position, in Fig. 2, and in its open position in Fig. 3, affording access to the matches 32.

Means for locking the rotating door 33, comprise a pivoted catch 36, extending outwardly

from the upper end of the hollow flange 35, as shown in Figs. 6 and 7, and it is adapted to be engaged and locked in an aperture 37 located at the lower end of a gate member 38, mounted for vertical reciprocation in the guideways 39. Mounted exteriorly of the cabinet and just above the door 33, are the raised numerals "1934", the numerals 1, 9 and 4 being affixed to the cabinet, while the numeral 3 is affixed to the top of the reciprocable gate member 38, to permit it to be vertically reciprocated in a slot in the front of the cabinet 10. A spring 41, secured to the inside of the front of the cabinet, and bearing against a boss 42, normally retains the gate member 38 in the position shown in Fig. 2, in which the catch 36 is engaged in the aperture 37, thus locking the rotating door 33. A guide piece 43 prevents lateral movement of the spring 41. A weight 44, secured to the outer end of an arm 45, secured to one end of the door 33, serves to close it whenever the operator lets go of the handle 33.

An alarm means, which is operated whenever the door 33 is opened, comprises a bell 46, which may conveniently be of the type used on bicycles, and has an operating arm 47 of conventional type, which is actuated by an arm 48, pivotally mounted on the inside of the cabinet 10 at 49, and provided with a slot 50 at its outer end, receiving the operating arm 47 of the bell 46, while its other end is pivotally secured to an arm 51, operatively secured on an end of the door 33. It is not intended to limit my invention to the specific alarm means shown, as various types of alarm means may be employed.

35. My device is used and operated as follows: The slideable back 19 is first removed from the cabinet 10, by pressing down on the back, against the spring-pressed bar 23, until the lip 20 at the top of the back 19 is below the upper edge of the back 40 of the container, so that the back 19 may be lifted out, thus affording access to the interior of the cabinet 10. The match box holder 26 is then lifted out of the brackets 28 and 29, supporting the pin 27, to which the holder 26 is secured and 45 is removed from the cabinet. A conventional box of matches 30, having the bottom part of one side cut away at 31, is inserted in the holder 26 in a vertical position, and the holder 26 with the box 30 is then placed in the container, as 50 shown in Figs. 2 and 3, with cut away portion 31 of the match box opposite the rotating door 33. The back 19 is then clamped on in an obvious manner.

55. The cabinet 10 is then placed in a convenient place in the kitchen near a stove, or other place where matches are to be used, and where children are likely to have access to them, if the matches are not locked in some sort of a container.

When a person desires to take a match from 60 the cabinet 10, he presses down the numeral 3 with one finger and takes hold of the hollow flange 35 on the rotating door 33. The downward movement of the numeral 3 carries down with it the sliding gate member 38, thus releasing the catch 65 36, mounted on the flange 35 of the door 33, and permitting the door 33 to be opened downwardly as shown in Fig. 5. The rotating opening movement of the door 33 lifts up the arm 51, secured to one end thereof, which in turn moves the end 70 of the arm 48 having the slot 50 therein downwardly, this causing the operating arm 47 received in the slot 50 to ring the bell 46 whenever the door 33 is opened.

75. The user then may take out a match 32 from the box holder 26, or from the match box 30, and

when the grip of the user's hand is released from the door 33, the weight 44 connected to the door by the arm 45 causes the door 33 to shut. The catch 36 then slips into the aperture 37 of the gate member 38, and securely locks the door, preventing further actuation of it until the numeral 3 is again pushed downwardly.

80. The invention herein shown may be conveniently used for storing articles other than matches, such as money, jewelry, and the like, and it is not intended to limit this invention to a match vault.

85. It will be apparent to those skilled in the art, that the invention herein disclosed may be variously changed, used or modified without departing from the spirit of the invention or sacrificing the advantages thereof, and that the embodiment of my invention herein is illustrative only, and that my invention is not limited thereto.

90. What is claimed is:

95. 1. A secured match vault, comprising a cabinet, a substantially cylindrically shaped door mounted horizontally on said cabinet, rotating on its longitudinal axis, and provided with a cut away portion through which matches may be reached 100 when the door is opened, means for supporting a box of matches in said cabinet in such a manner that a part of one end of such box is within said rotating door, and a locking means for said door.

105. 2. A secured match vault, comprising a cabinet, a substantially cylindrically shaped door mounted horizontally on said cabinet, rotating on its longitudinal axis, and provided with a cut away portion through which matches may be reached 110 when the door is opened, means for supporting a box of matches in said cabinet in such a manner that a part of one end of such box is within said rotating door, a locking means for said door, and alarm means operatively connected with said door 115 so that said alarm means are operated whenever said door is opened.

120. 3. A secured match vault, comprising a cabinet, a substantially cylindrically shaped door mounted horizontally on said cabinet, rotating on its longitudinal axis, and provided with a cut away portion through which matches may be reached 125 when the door is opened, means for supporting a box of matches in said cabinet in such a manner that a part of one end of such box is within said rotating door, a locking means for said door, a sound alarm means, and linkage between said door and said alarm adapted to sound said alarm whenever said door is opened.

130. 4. A secured match vault, comprising a cabinet, a substantially cylindrically shaped door, mounted on said cabinet, rotating on its longitudinal axis, and provided with a cut away portion 135 on its side through which matches may be reached when the door is opened, a catch on said door, a reciprocable gate member in the cabinet having an aperture adapted to receive said catch on said door, for locking said door, and hand operated means on the outside of the cabinet and secured to said gate member, for reciprocating said gate member to release said catch to permit said door to be opened.

140. 5. A secured match vault, comprising a cabinet, a substantially cylindrically shaped door, mounted on said cabinet, rotating on its longitudinal axis, and provided with a cut away portion on its side through which matches may be reached 145 when the door is opened, a catch on said door, a reciprocable gate member in the cabinet having an aperture adapted to receive said catch on said 150 door.

door, for locking said door, hand operated means on the outside of the cabinet and secured to said gate member, for reciprocating said gate member to release said catch to permit said door to be opened, and means for automatically closing said door when it is released by the user.

6. A secured match vault, comprising a cabinet, a substantially cylindrically shaped door, mounted on said cabinet, rotating on its longitudinal axis, and provided with a cut away portion on its side through which matches may be reached when the door is opened, a catch on said door, a reciprocable gate member in the cabinet having an aperture adapted to receive said catch on said door, for locking said door, hand operated means on the outside of the cabinet and secured to said gate member, for reciprocating said gate member to release said catch to permit said door to be opened, and alarm means operatively connected with said door so that said alarm means are operated whenever said door is opened.

7. A secured match vault, comprising a cabinet, a substantially cylindrically shaped door, mounted on said cabinet, rotating on its longitudinal axis, and provided with a cut away portion on its side through which matches may be reached when the door is opened, a catch on said door, a reciprocable gate member in the cabinet having an aperture adapted to receive said catch on said door, for locking said door, hand operated means on the outside of the cabinet and secured to said gate member, for reciprocating said gate member to release said catch to permit said door to be opened, alarm means operatively connected with said door so that said alarm means are operated whenever said door is opened, and means for automatically closing said door when it is released by the user.

8. A secured match vault, comprising a cabinet, a substantially cylindrically shaped door, mounted on said cabinet, rotating on its longitudinal axis, and provided with a cut away portion on its side through which matches may be reached when the door is opened, a catch on said door, a reciprocable gate member in the cabinet having an aperture adapted to receive said catch on said door for locking said door, and indicia on the outside of said cabinet, one of said indicia being secured to said gate member for reciprocating said gate member to release said catch to permit said door to be opened.

9. A secured match vault, comprising a cabinet, a substantially cylindrically shaped door

mounted horizontally on said cabinet, adapted to be rotated on its longitudinal axis, and provided with a cut away portion on its side, through which matches may be removed when the door is opened, means for supporting a box of matches in said cabinet in such a manner that a part of one end thereof is within said rotating door, a catch on said door, a reciprocable gate member in the cabinet having an aperture adapted to receive said catch on the door for locking the door, and hand operated means on the outside of the cabinet and secured to the gate member, for reciprocating the gate member, to release the catch to permit the door to be opened.

10. A secured match vault, comprising a cabinet, a substantially cylindrically shaped door mounted horizontally on said cabinet, adapted to be rotated on its longitudinal axis, and provided with a cut away portion on its side, through which matches may be removed when the door is opened, means for supporting a box of matches in said cabinet in such a manner that a part of one end thereof is within said rotating door, a catch on said door, a reciprocable gate member in the cabinet having an aperture adapted to receive said catch on the door for locking the door, hand operated means on the outside of the cabinet and secured to the gate member, for reciprocating the gate member, to release the catch to permit the door to be opened, and means for automatically closing said door when it is released by the user.

11. A secured match vault, comprising a cabinet, a substantially cylindrically shaped door mounted horizontally on said cabinet, adapted to be rotated on its longitudinal axis, and provided with a cut away portion on its side, through which matches may be removed when the door is opened, means for supporting a box of matches in said cabinet in such a manner that a part of one end thereof is within said rotating door, a catch on said door, a reciprocable gate member in the cabinet having an aperture adapted to receive said catch on the door for locking the door, hand operated means on the outside of the cabinet and secured to the gate member, for reciprocating the gate member, to release the catch to permit the door to be opened, and alarm means operatively connected with said door so that said alarm means are operated whenever said door is opened.

TOM J. KULURIS.
